UNITED STATES PATENT OFFICE.

OSCAR E. PETERSEN, OF DES MOINES, IOWA.

DIRIGIBLE REFLECTOR AND BURNER.

1,045,608.

Specification of Letters Patent.

Patented Nov. 26, 1912.

Application filed November 8, 1911. Serial No. 659,568.

To all whom it may concern:

Be it known that I, OSCAR E. PETERSEN, citizen of the United States of America, and resident of Des Moines, Polk county, Iowa, have invented a new and useful Dirigible Reflector and Burner, of which the following is a specification.

The object of this invention is to provide means for conjunctively turning the burner and reflector of a head-light, independent of the casing containing such burner and reflector, coincident with a turning of a carriage on which said head-light is mounted.

A further object of this invention is to provide means for adjusting connections between burner and reflector turning devices and the steering mechanism of a carriage.

A further object of this invention is to provide improved means for supplying illuminating gas to a dirigible reflector and burner.

My invention consists in the construction, arrangement and combination of elements hereinafter set forth, pointed out in my claims and illustrated by the accompanying drawing, in which—

Figure 1 is a front elevation and Fig. 2 a vertical section illustrating my improved device in position for practical use. Fig. 3 is a horizontal section on the indicated line 3—3 of Fig. 2, illustrating the adjustable connections between the turning devices and steering bar of a carriage.

In the construction of the device as shown the numeral 10 designates a yoke or fork adapted to be mounted on a carriage in the ordinary way, either at the center or one side at the front of the carriage. The yoke or fork 10 is formed with a tubular supporting stem 11 and a pipe 12 is mounted through said stem and arranged loosely therein. A ball race or cup 13 is fixed to the yoke or fork 10 and a mating ball race or cup 14 is fixed to the pipe 12 above and in inverted relations to the first cup. Bearing balls 15 are interposed between the cups or ball races 13, 14, thus providing a roller bearing and support for the pipe 12 in the yoke or fork 10. A lamp casing 16 of any desired construction is mounted in the usual way on the fork or yoke 10 and the pipe 12 extends through the bottom of said casing and carries a burner 17 on its upper end. I have illustrated the burner 17 as adapted for the use of acetylene gas as that is the illuminating fluid now commonly used on

automobiles, and such gas may be conveyed to the pipe 12 through a tube 18 leading from a source of supply (not shown), said tube being secured to a nipple 19 opening rearwardly from the pipe below the casing 16. A reflector 20 is mounted on the upper end portion of the pipe 12 within the casing 16 and is adjustable circumferentially and longitudinally of said pipe by means of a set screw 21. I prefer such adjustment of the reflector 20 on the pipe 12 that the axis of the reflector if extended horizontally would intersect a point at the center of the flame supplied by the burner 17. A rod 22 is fixed at its upper end in and closes the lower end portion of the pipe 12 and said rod is bent laterally at its lower end. An arm 23 is secured to the laterally extending lower end portion of the rod 22 by bolts 24 and may be adjusted thereon longitudinally. The rod 23 is formed with a slot 25 and extends across a steering bar 26 of any desired form. A bolt 27 is mounted through the steering bar 26 and extends loosely through the slot 25 of the arm 23. Any desired means may be employed for reciprocating the steering bar 26 to govern and control direction of travel of a carriage such as an automobile, and the same forms no part of my invention. Any reciprocation of the steering bar 26 will be communicated through the bolt 27 and arm 23 to an oscillation of the rod 22 on a vertical axis and such oscillation is communicated directly to the pipe 12. Inasmuch as the pipe 12 carries the burner 17 and reflector 20, any oscillation of said pipe results in a corresponding oscillation of the burner and a movement of the reflector coincident therewith through an arc and maintains the relations above described of the axis of the reflector and flame from the burner. The tube 18 is made of flexible material to compensate for any oscillation of the pipe 12. The loose connection of the bolt 27 with the arm 23 through the slot 25 compensates for arcuate travel of the bolt or vertical vibration of the steering bar 26 relative to said arm.

I claim as my invention—

1. A dirigible reflector and burner for automobile head-lights, comprising a yoke having a tubular stem, a pipe mounted through said stem, a casing carried by said yoke, said pipe extending within said casing, a burner carried by said pipe within the casing, a re-

2. A reflector mounted on said pipe within the casing, means for supplying fuel to said pipe, and means for oscillating said pipe on a vertical axis.
5. A dirigible reflector and burner for automobile head-lights, comprising a yoke having a tubular stem, a pipe mounted through said stem, a casing carried by said yoke, said pipe extending within said casing, a burner carried by said pipe within the casing, a reflector adjustably mounted on said pipe within the casing, means for supplying fuel to said pipe, and means for oscillating said pipe on a vertical axis.
10. 3. A dirigible reflector and burner for automobile head-lights, comprising a yoke having a tubular stem, a casing in said yoke, a pipe mounted for oscillation in said stem and casing, a ball race on said yoke, a ball race on said pipe, balls interposed between said races, an actuating rod fixed to said pipe, a fuel tube communicating with said pipe, a burner on said pipe within the cas-

ing, and a reflector carried by said pipe within said casing.

4. In a device of the character described, the combination with the steering rod of a self-propelled vehicle, of a lamp, a rod extending upwardly through the bottom of said lamp and provided throughout a portion of its length with a longitudinally extending bore, a burner carried by the top of said rod and communicating with said bore, means for supplying fuel to said bore, a laterally directed arm carried by the upper end of said rod, a reflector carried by said arm and means operable by the steering rod for turning said rod together with the burner and reflector.

Signed by me at Des Moines, Iowa, this 40
thirty-first day of January, 1911.

OSCAR E. PETERSEN.
